UNITED STATES PATENT OFFICE.

ESTHER LENZIKOW, OF NEW YORK, N. Y.

SLIP COVER FOR GARMENTS.

Application filed January 22, 1925. Serial No. 3,900.

This invention relates to improvements in slip covers for garments, and has for one of its objects to provide an improved cover or bag of simple and inexpensive construction 5 in which a garment may be easily and quickly suspended and entirely enclosed to protect the same from an accumulation of dust thereon and from which the garment may be readily removed.

10 The above and other objects will appear more clearly from the following detailed description, when taken in connection with the accompanying drawing, which illustrates a preferred embodiment of the inventive idea.

In the drawing—

Figure 1 is a front elevation of the slip cover in operative position, partly broken away and shown in section;

20 Figure 2 is a vertical section on the line 2—2 of Figure 1; and

Figure 3 is a transverse section on the line 3—3.

The cover of the present invention is particularly designed for the purpose of protecting garments such as waists, coats and the like and may be made of any suitable material such as cloth, so that the cover or bag may be folded into compact form when 30 not in use.

The cover is preferably formed to simulate in general outline the kind of garments it is capable of receiving and consists of a body including a back section 4 formed of a single piece of material to which is secured a front section, generally indicated by the numeral 5. This front section includes a yoke 6 and bottom portions 7. The yoke 6 is cut to conform to the shape of the 35 upper portion of the back section 4 and is secured thereto by stitching or otherwise. The yoke 6 extends across the width of the back and downwardly a short distance from the top thereof. The upper edge of the 40 bottom portions 7 is stitched to the lower edge of the portion 6, as indicated at 8, and further stitched to the edges of the back section 4, as indicated at 9, so that when the cover is closed the same will form a complete enclosure for the garment. 10 suspended in the cover. Medially of the top of the cover the same is provided with a small opening 11 through which the shank of the

hook 12 of a curved hanger 13 may be extended, the body portion of said hanger being disposed within the cover and capable of suspending said cover and the garment therein.

Intermediate the vertical side edges of the bottom portions 7 of the front section said portion is cut vertically to provide an opening 14 which extends from the lower edge of the yoke 6 to the bottom edge of the front portions 7. The adjacent edges forming the opening are overlapped and intermediate the top and bottom thereof are provided with suitable securing means such as the snap fastener 15 which may be utilized to close the opening 14 after a garment has been placed in the cover, which may be readily done without entirely removing the hanger 13 therefrom.

The portions 7 may be provided with a pocket 16 for receiving a girdle or belt which, if desired, may be detached from the 75 garment and put in the pocket before the garment is placed in the cover.

What is claimed is:—

A slip cover for garments, including a back section, a front section including a 80 yoke and a bottom portion, said yoke extending across the width of said back section and having its upper and lower edges secured, respectively, to the upper edges of said back section and bottom portion, and the upper edges of said yoke and back section having an opening, said bottom portion 85 having its vertical and bottom edges secured, respectively, to the vertical and bottom edges of said back section and being slit 90 medially of its vertical edges to form an opening extending from the bottom edge of said yoke to the lower edge of said bottom portion to provide a centrally disposed opening through which a garment may be 95 inserted for suspension upon a hanger the hook of which projects through the first named opening, and means for securing together the edges of said bottom portion forming the second named opening whereby 100 said garment will be entirely enclosed within the slip cover.

In testimony whereof I have affixed my signature.

ESTHER LENZIKOW.
